TYPEWRITING MACHINE

Burnham C. Stickney, Hillside, N. J., assignor to
 Underwood Elliott Fisher Company, New York,
 N. Y., a corporation of Delaware

Application August 29, 1931, Serial No. 560,148

51 Claims. (Cl. 197—30)

This invention relates to the type-operating systems of typewriting machines, especially those of the portable noiseless class.

In standard-size noiseless machines, the types are mounted upon the ends of radial slides, moving horizontally, and normally extending very far in front of the platen, and so requiring more space than can be afforded in a portable machine. Hence portable noiseless machines have been 10 made with swinging type-bars substituted for slides. Each of said portable type-bars, however, has been provided with only two types, so that the number of type-bars equals the number of keys.

15 It is a feature of the present invention to provide each noiseless swinging type-bar with four types, to be operable by either of two keys, thus reducing the number of noiseless pivoted type-bars to half the number of the keys, and greatly 20 compacting the type-bar system.

One advantage of lateral compactness is that the types move in paths which are at right angles to the platen, or nearly so, conducing to good type-impressions. Another advantage is in the reduction 25 in the number of parts, since every type-bar is provided with an impression-toggle and also with a transmission-toggle, in addition to the key-driven operating trains.

One of the features is in the nature of a noise- 30 less compound toggle-mechanism which is practicable for a swinging type-bar provided with four types.

The type-bars may stand in front of the platen, being pivoted at their lower ends in an arc. Each 35 impression-toggle may be pivoted at one end to its type-head, and to the machine-framing at the forward toggle end. The four types are so placed upon the bar that when in printing position they substantially coincide at four points 40 with an arc struck from the fixed or forward pivot of the silent impression-toggle.

When one key is operated, the type-bar swings back through a simple arc, to bring into use either 45 of the two upper types. When the other key is operated, the same type-bar is automatically lifted, to bring into action either of the two lower types thereon; and at the same time the type-bar swings back to the platen.

The impression-toggle is equally efficient in 50 each of the two printing positions of the type-bar, inasmuch as the four types are equally distant from the fixed pivot of the silent-impression toggle, as just explained.

55 The type-bar is lifted by means of its lower end, the fulcrum of the type-bar being swung up in a

short arc, so that the two lower types are brought to the exact positions, relatively to the platen, that were previously occupied by the two upper types.

The silent-impression toggle is extended at the 60 swinging of the type-bar, and the type-impression is due to a flying weight, whose momentum is transmitted by another toggle, to actuate the impression-toggle at the moment of impression. 65 The transmission-toggle extends from the type-bar to the impression-toggle, and the latter extends from the type-bar to the fixed pivot.

Of the two keys that are provided for each type-bar, one lifts the type-bar for printing the lower 70 types thereon, and by so doing, this key causes the type-bar also to swing rearwardly to the platen; the type-bar therefore having a floating movement.

The other key is connected merely to swing the 75 type-bar in a simple arc, just enough to bring into play the upper types thereon.

Each of the two keys has an individual operating toggle. These operating toggles are normally extended. The operating toggle which is flexed by one key, operates to lift the type-bar; while the other operating toggle remains in its normally extended condition and takes part in the described floating movement of the type-bar. The other key flexes the other operating toggle, 85 thereby merely swinging the type-bar in a simple arc; the type-bar at this time being locked against rising, by means of the other of the operating toggles.

Each of these operating toggles is therefore 90 useful for two purposes; each having a type-bar swinging function, and also a steady or locking function. In other words, when one operating toggle is being flexed, the other operating toggle effects the required locking.

Each of these operating toggles is provided 95 with a shoulder for restoring the other toggle to home position, in case it should become necessary in high speed of operation.

The type-bars, with their noiseless toggles, and 100 their operating toggles, are all radial; every set of four toggles operating in the same radial plane with its type-bar.

The system of type-bars being very narrow, and the system of key-levers being very wide, a 105 novel connection is disclosed from the levers to the operating toggles. For this purpose the levers are divided into a middle group and two side groups. In the middle group there are as many levers as there are type-bars; and every lever in the middle group is directly connected to a type-

bar-operating toggle; the width of this middle group being substantially equal to the width of the system of operating toggles.

Said system of operating toggles includes two rows of pivoted arms, one row above the other, and the levers of said middle group are connected to the lower row of arms by means of simple vertical links.

The key-levers in the left-hand group and the key-levers in the right-hand group are all connected to the operating arms in the upper row. This connection is made by means of outlying cross-levers, half of them extending towards the left and half towards the right. Said cross-levers are connected to the arms and the key-levers by pendent links. Free action is thus secured, or liability to bind and cramp is avoided, while the parts are sufficiently separated, space is saved, each train consists of a few simple parts, and expense is reduced.

If each type-carrier in a noiseless machine is operable by means of two key-levers which are adjacent to each other, it may happen in some cases, where the two types often fall next to each other in printing (as for instance the type d and the type e that in rapid operation there will be a false action of the operating-toggle mechanism, due to it not having time to resume normal position after printing one type, before it is operated in another way to print the other type.

To avert this difficulty, it is contrived by the present invention to provide each type-bar with letters or characters which are not usually operated in immediate succession, so that no type-bar may be operated to print its two types, unless there is an intervening operation of some other type-bar.

For this purpose, the outlying cross-levers, which connect all the key-levers to all the type-bars, are arranged out of uniform alphabetical order with respect to the key-levers. It will be understood that the order of the types which are operated by the key-levers in the middle group, agrees with the alphabetical order of the keys in that group; but the cross-levers afford a choice of alphabetical connection in respect to the outer groups of key-levers. The first cross-lever may be connected to either the first, second, third or fourth key-lever, for example, in either side group. Similar selection may be made for the second, third and other cross-levers, so that the types upon the type-bars may be altogether out of correspondence with the order of the keys in the left-hand and right-hand groups, to the end that no type-bar shall have different types that are operated in immediate succession in usual run of work.

Certain features of the invention are also useful in other kinds of typewriters.

Other features and advantages will herein-after appear.

In the accompanying drawings,

Figure 1 is a diagram, showing a sectional and side elevation of a type-bar, with its impression and transmission toggles.

Figure 2 is a sectional elevation of the machine, taken from front to rear, showing the parts in normal positions.

Figure 3 is a similar section, showing the type-bar swung by the key to bring the upper types into use.

Figure 4 shows the same type-bar swung by another key to bring either of the lower types into use.

Figure 5 is a cross-sectional plan of the type-

bar and linkage system, with the underlying cross-levers and key-levers.

Figure 6 is a diagram similar to Figure 5, but showing one manner of assorting the connections between the type-bars and the flanking groups of key-levers, to provide each type-bar with non-consecutive types.

Upstanding type-bars 10 swing radially back to the printing point on a platen 11, a little above a horizontal plane, that passes through the axis of the platen, as is usual in the Underwood portable typewriter. The pivoting of the lower ends of the type-bars at 12, enables them to swing in simple arcs.

There are shown twenty-one type-bars, operable by forty-two keys 13. The planes of the type-bars converge from front to rear, with the apex at the printing point. The type-bars are very compact considered laterally, so that the direction of printing movement of even the extreme right-hand or left-hand type-bar at Figures 5 does not vary objectionably from a true right-angle movement relatively to the platen, thus avoiding the necessity of providing an excessive angularity of the type-face relatively to the type-bar at Figure 5, and enabling the printing pressure to be applied against the platen practically in the plane of swinging movement of the type-bar, thus conducting to good impressions; the final movement of the type being controlled by a fixed center guide 14, having its guiding faces exactly at right angles to the platen.

At Figure 3 it will be seen that printing may be effected by either one of the upper or lower case types 15 carried upon the tip of the type-bar, 110 dependent upon the position to which the platen 11 is shifted; the type-bar having a simple swinging movement about the pivot 12, the type-path being a simple arc from normal position to the platen.

The type-bar at Figure 3 is driven by a key 13, upon a stem 16 rising from a U-shaped lever 17, the rear upper end of which is pivoted at 18. This key-lever is one of those at the sides of the machine. This pivot 18 may be nearly on a level 120 with the keys 13 in the two rear rows, the keys descending in nearly vertical paths. The type-operating train includes a vertical pull-link 19 which connects key-lever 17 to the depressible arm 20 of a cross-lever 21, said cross-lever 125 having an inner arm 22, from the end of which depends a vertical pull-link 23, which at its lower end is pivoted to an operating arm 24. The latter is pivoted upon a stationary transverse curved fulcrum-bar 25, and swings upwardly at 130 the depression of the key, as shown at Figure 3.

This arm 24 operates, by means of a rearwardly-extending link 26, a short arm 27 upon the type-bar and extending below its pivot 12. The arm 24, as it swings up, pulls upwardly and 135 forwardly the link 26, and thereby rocks the short arm 27 of the type-bar from the dotted-line to the full-line position at Figure 3. This carries the type-bar fully or approximately to the platen.

A spring 28 may be connected to each cross-lever 21, for returning the key and type-train to normal position, with the operating toggle 24, 140 26 substantially straightened out, as at Figure 2.

It may now be noted at Figure 5 that the compact system of type-bars is very much narrower than is the system of key-levers, and that the cross-levers 21 reach from the type-bars to the outlying key-levers, and that the direction of impulse is directly in the plane of the moving part. 145

This avoids all tendency to side strain and cramping of levers and links, thus securing an entirely free action, and provides a simple, inexpensive, compact and accessible linkage.

5 The cross-levers 21 may be placed one in front of another, as shown at Figure 5, with the rear-most cross-lever connecting the outermost key-lever to the outermost type-bar, the next cross-lever connecting the next inner key-lever to the 10 next inner type-bar, and so on.

Different outer links 19 are attached to their key-levers at different points in the lengths of the latter, but this variation is compensated for and uniform depth of key-strokes is secured, by 15 suitably varying the proportions of the cross-levers 21, so that equal type-bar strokes are produced by equal key-depressions.

The cross-levers 21 may be pivoted in hangers 29 depending from a curved overlying cross-plate 30, secured by screws 31 to posts 31^a upon the ends of a segment 32, upon which the operating arms 24 are pivoted and guided; the operating arms 24 and links 26 working in the same radial planes as their respective type-bars, and 25 said arms 24 overhanging the segment 32. The hangers 29 are fastened at irregular points to the hanger plate 30, as at Figure 5, and each lever 21 has its proper individual leverage, for 30 equalizing the key-strokes. The operating arms 24 may be of equal length throughout the system; but the levers 21 may vary from one another in total length, as well as in the relative lengths of 35 individual arms.

Keys 34 in the two front rows are mounted upon stems 35 rising from the forward ends of levers 36, the latter having upwardly and rearwardly extending rear arms 37, pivoted at 38 upon a fixed cross-rod, the latter being nearly level with the keys 34. It will be seen that levers 40 36, which carry the front keys, are longer than levers 17 which carry the rear keys, and that the levers 36 extend rearwardly of the levers 17, and also that the fulcrum-rod 38 of the long key-levers may be somewhat lower than the fulcrum-rod 18 of the short key-levers. All the keys are 45 guided about vertically, and have uniform action.

All the key-levers at the middle of the machine are directly connected by vertical pull-links 39 with radial operating arms 40, which are pivoted 50 upon a curved fulcrum-wire 41 and form a lower set. When an operating arm 40 is pulled down by its key-lever, link 42 is pulled forwardly, and thereby a short radiating fulcrum-lever, having a forward arm 43 and a rearward arm 44, is 55 rocked about a curved pivot-wire 45.

The arm 44 carries the aforesaid type-bar fulcrum-pin 13 and said fulcrum-pin 12 is swung upwardly and rearwardly through an arc 46, Figure 4, thereby elevating the type-bar, to cause 60 the lower types 33 thereon to print upon the platen, according to the case-shifting of the latter, Figure 4.

During the operation of the type-bar 10 by an arm 40, said type-bar floats bodily in upward 65 and rearward direction, since the fulcrum-arm 44, the short type-bar arm 27 and the link 26 are combined to form a linkage. The link 26 is pivoted at 47 to the type-bar, and at 48 to the arm 24, and the pivots 47, 48 and 25 are in line 70 at the moment of printing, thus forming in effect a rigid link that extends from 47 to 25. The parts 24 and 26 taken together may be regarded as forming one member of the three-part linkage.

The spring 28 normally holds the upper operating arm 24 down against a stop 50, which con-

sists of the upper edge of the segment 32, and the link 26 may swing slightly up from the normal Figure 2 position to the position seen at Figure 4, thus straightening the operating toggle 24, 26, and thereby furnishing rigid support for the arm 27 at the moment of printing.

The path through which types 33 float at the operation of the arm 40, is seen at 49, Figure 4; this path being approximately at right angles with the platen.

It is seen that when printing the upper types, the type-bar swings upon a single stationary fulcrum 12, but that when printing the lower types, the type-bar floats upon the fulcrum 12 and the pivot 47, the fulcrum 12 rocking about the stationary pivot 45, and pivot 47 moving substantially concentrically with pivot 48, which is stationary at this time.

Hence each type-bar may be operated by either of two keys, and its types are brought into use selectively by the key operated.

Upon release of the key, a spring 51 returns the lower operating arm 40, and straightens out the operating toggle 40, 42, and rocks the fulcrum-lever 43, 44 back from Figure 4 position to normal position; the upper operating arm 24 remaining stationary, and its link 26 dropping to the dotted-line position at Figure 4.

The spring 51 normally holds the lower operating arm 40 against a stop 52 formed upon the lower edge of the segment 32; so that 40, 42 may normally form a rigid toggle, and hold the fulcrum-lever 43 motionless when any outer key-lever is being operated, as at Figure 3; said toggle 40, 42 locking the fulcrum-lever 43, 44 against motion during the Figure 3 operation.

Half of the key-levers form a group at the middle of the system; and the levers in this half carry keys in all four rows. The remaining key-levers are divided to form two outer groups, these 115 being connected by cross-levers 21 to the type-bars. Twenty-one lower operating arms 40 are directly connected by the links 39 to the twenty-one key-levers forming the middle group. Eleven key-levers are shown in the left-hand outer group, 120 and ten in the right-hand outer group; but none in these outer groups drives the lower operating arm 40. Instead, said outer groups are connected by the two divergent groups of cross-levers 21 with the upper operating arms 24.

Thus the wide key-lever system is divided into three groups, the middle group having about the same width as the type-bar system, and being connected directly thereto, while the other groups extend at each side far beyond the type-system, 130 and are connected by the right-hand and left-hand groups of cross-levers to the entire system of radial type-operating trains.

This system is especially efficient for a machine where each type-bar is operable by two 135 keys, since two keys which operate any type-bar do not need to be next to each other, or even adjacent, for one key-lever may be in the middle group and the companion key-lever may be in one of the flanking groups. It will be seen that a 140 type-bar may be operated by keys which are remote from each other, one key being connected to the type-bar through the cross-lever 21, and the other key being connected to the type-bar directly by the link 39. The novel adaptation of a narrow 145 type-system to a wide key-lever system is available for general use in typewriting machines, not being limited to the specific type-bar mechanism which is herein disclosed.

The operating arms 40 are in proximity to the 150

key-levers which operate them, and are directly connected thereto by links 39, which are well spaced from the links 19; the latter being connected only to the levers in the outer two groups 5 of key-levers, while the former are connected only to the key-levers in the middle group. The levers 21 are above the segment 32 and above the systems of radial operating toggles, and are readily accessible and easily assembled, and do not take up room that is wanted for other members of the system of type-bar trains.

The toggle-link 26 may be provided with a restoring lug or shoulder in the form of a pin 53 serving to straighten out the alternate toggle 40, 15 42 for the same type-bar 10, in case said toggle 40, 42 needs to be straightened, as might occur in rapid operation of the machine. The position of the shoulder 53 for this service is seen at Figure 3.

20 The link 42 is provided with a similar restoring shoulder or pin 54, to straighten out the toggle 24, 26 if it should happen to be necessary; the position of the shoulder 54 for this service being seen at Figure 4. These shoulders 53 and 54 may further be depended upon to coat with the stops 50 and 52 to hold the toggles each rigid, as required.

25 The short levers 43, 44 may work in slots 55 formed in a segment 56, said slots radiating to the printing point, and the pivot-wire 45 being curved concentrically with the printing center, or with a tangential line 57 extending downwardly and forwardly from the printing point on the platen. This segment may form a frame-member 30 including side bars 58 and arms 59 supporting the segment upon the side walls 60 of the typewriter-frame. The forward member of the frame may be the segment 32, supporting the operating-arm system.

35 Said radial slots 55 and wire 45 are at the rear border of the segment 56, and the operating toggles for said fulcrum-levers may extend forwardly over said segment 56 and downwardly beneath the forward segment 32. The other operating 40 toggles may extend forwardly under said segment 56, and forwardly over the forward segment 32.

45 In operating any key in the middle group, motion is transmitted to the type-bar by the short radial fulcrum-lever 43, 44, which at its forward end is pulled down by the key, and at its rear end swings up and carries the type-bar bodily upward, to enable either of the lower types to print. This lifting movement of the type-bar is taken 50 advantage of to cause the type-bar simultaneously to swing rearwardly upon the fulcrum 12, this swinging motion being brought about by the idle toggle 24, 26, as above described. This idle toggle remains substantially straightened out 55 during the type-bar lifting movement of the short fulcrum-lever 43, 44, and serves to cause the pivot 47 at the lower tip of the type-bar to swing up in an arc substantially concentric with pivot 48.

60 Hence the type-bar, in being lifted by the fulcrum-lever 43, 44, is restrained by said idle toggle 24, 26, and the type-end of the type-bar is caused to swing rearwardly. Thus the toggle 24, 26, or the link 26 alone, serves as one of the type-bar floating elements at Figure 4, but serves 65 as the type-bar operating element at Figure 3.

70 The toggle-element 40, 42 serves as a steady-ing link to hold the fulcrum-lever 43, 44 stationary at Figure 3, so that the type-bar may swing truly in a simple arc about the fulcrum 12, while 75 in Figure 4 said toggle 40, 42 is used for vibrating

the fulcrum-lever 43, 44 to lift the type bar as described.

Thus each operating toggle is capable of two functions. The stroke of each key brings each toggle into use, one toggle for moving the type-bar, and the other toggle for controlling the main pivotal movement of the type-bar, either by holding the fulcrum or main pivot 12 stationary at Figure 3, or by causing the type-bar to be carried up bodily by said pivot, Figure 4.

80 The foregoing mechanism may bring the type-bar at Figure 3 or Figure 4 close to the platen; and the final depression may be noiselessly delivered by the aid of a flying weight 61. The weight normally occupies a low position at Figure 2, but is connected to the type-bar to swing upwardly and rearwardly at high speed, its momentum being employed to press the type against the platen, Figures 3 and 4. This weight 61 is formed upon an arm 62, which is pivoted at 63 to an arm 64 that projects forwardly from the type-bar 10 between its ends. Said weight-arm 62 is pivoted at 65 to a link 66, and combines therewith to form a momentum-transmitting toggle; and this toggle is effective upon a radial 90 pressure-toggle, the latter consisting of lever 67 and link 68. Link 68 is pivoted at 69 to the type-head 70 on the type-bar. The middle pivot of the pressure-toggle is seen at 71, and its forward pivot at 72.

95 All the four toggles in each train are radial and operate in the same plane with their type-bar. The levers 67 are guided in radial slots 73 formed in an upper segment 74, which is fixed to the framing of the machine.

100 The pressure-toggle 67, 68 is folded in normal position, Figure 2. The rearward swinging of the type-bar (Figure 3 or 4) pulls the weight-arm 62 rearwardly, to drive the link 66 upwardly, while the same link 66 is also lifted from normal position by the opening of the impression-toggle 105 67, 68, owing to its connection with the type-bar at 69.

110 The pressure-toggle 67, 68 is folded in normal position, Figure 2. The rearward swinging of the type-bar (Figure 3 or 4) pulls the weight-arm 62 rearwardly, to drive the link 66 upwardly, while the same link 66 is also lifted from normal position by the opening of the impression-toggle 115 67, 68, owing to its connection with the type-bar at 69.

115 It will thus be noted that both the transmission-toggle 67, 68 and the impression-toggle 62, 66 are connected to the same type-bar, both toggles to be opened out by the travel of the type-bar to the platen. When the type is nearly in printing position, the speed of the weight 61 is very high, and it serves to straighten out its toggle 62, 66, as at Figures 3 and 4, and thereby straightens out the impression-toggle 67, 68, and so forces the type silently and with sufficient pressure against the work-sheet.

120 The arm 62 at the conclusion of its printing stroke slightly flexes a spring-finger 75 upon the type-bar arm 64, and this spring absorbs some of the momentum of the weight 61. When the printing is done, the spring serves to start the arm 62 and the other parts of the linkage away 125 from the platen, towards normal position; and this return is aided by the spring 28 or spring 51, and also by spring 76, which is connected to the arm 77 of a universal-bar bail 78. The latter is operated by fingers 79 on the key-levers, and 130 is connected at 80 to any suitable or usual carriage-feeding and ribbon-vibrating mechanism, not shown, said universal bail being fulcrumed at 81 upon the machine-frame.

135 The fulcrum-levers 43, 44 work in the same radial planes as the type-bars, the transmitting and impression toggles and the operating toggles. At their forward ends the system of radiating trains is of a width substantially equal to the width of the middle group consisting of half of 140 150

the key-levers, and all the links 39 may stand substantially vertical, and therefore work in the radial planes of the type-bar trains, and also in the parallel planes of the key-levers, without 5 cramping. This desirable feature of connection of the type-bar trains to the key-levers is rendered practicable by the use of the groups of outlying cross-levers to connect the radial type-bar trains to the remaining half of the key-levers, 0 said cross-levers being divided equally into groups, one division going to the left and the other division going to the right of the key-lever system. The key-levers may be parallel and all work freely in vertical planes.

5 Thus is provided a simple, compact, inexpensive, accessible and well-ordered system of key and type actions.

If it should be considered that the impression-toggle 67, 68, the transmission-toggle 62, 66 and 10 the type-bar 10 taken together form a unit, then it will be observed said unit occupies a position at Figure 4 as if it had been swung bodily up around the forward stationary pivot 72, as compared with the position of the unit at Figure 3. 15 The type-bar fulcrum 12 is mounted to swing through an arc 46 in an upward direction to agree with such swinging of the unit bodily about the point 72. Said stationary pivot 72 remains unchanged throughout all operations of the type-bar and its toggles, and maintains a fixed distance from the platen. An arc struck from said pivot point would be tangent to the printing point in both positions of the platen; and said arc would moreover substantially coincide with all 20 four type-faces on the type-bar. In other words, when the impression-toggle 67, 68 is expanded, all four types are equally distant from said fixed pivot 72.

A line extended through the straightened-out impression-toggle 67, 68 from said fixed pivot 72, 25 passes midway between the upper two types and the lower two types. This aids in accurately proportioning the parts and in securing the above-named accurate results and other desirable 30 features. Moreover, the printing pressure which is furnished by the toggle 67, 68, is applied at a point wh'ch is nearest to all four types, thus tending to uniformity of impressions of the types, and ease of manufacture and repair. The toggle 35 works directly upon the type-head at either Figure 3 or Figure 4, without detriment to the printing from springing or weakness of the type-bar. At Figure 3 the extended toggle is inclined downwardly more than at Figure 4, but the efficiency 40 of the type-action is substantially the same. It is thus contrived to call the impression device into action for either a simple swinging motion of the type-bar as at Figure 3, or a bodily rising and swinging motion as at Figure 4, and in either 45 case the impression-toggle 67, 68 reaches the same high degree of efficiency, and accomplishes the same work as in the other case. Hence four types may be used upon the type-bar, and all the types may be impressed 50 noiselessly upon the platen, by the same toggle-train, working in the same way; the toggle-train having only one point of connection (72) to the fixed framing of the machine, and the other points of connection (63, 69) being to the type-bar itself, one point (69) being at the type, and the other point being between the type and the type-bar fulcrum 12.

It will be seen that the requirement for compactness in a portable machine is met by employing a system of upstanding type-bars in front 55

of the platen, and contriving not only to form trains of silent impression mechanism for said bars, but also to mount four types upon each bar, and operate each bar by means of two keys. The height of the machine need not exceed the usual 80 height for portables, and the distance forwardly from the platen to the keyboard need not exceed the usual distance, and is far less than has been heretofore found to be practicable in noiseless machines in which each printing slide has 85 four types.

The operation of each noiseless type-bar train by means of two keys permits compacting the noiseless system of type-bars and toggles in a very small space, considered widthwise of the machine, and gives a much better angle of incidence of the types against the platen than has heretofore been considered practicable in noiseless type-bar portable machines. The provision 90 of the outlying cross-levers connecting all the type-bars to the two outer groups of key-levers, and connecting the middle group directly to the type-bars conduces to compactness, simplicity and cheapness, and permits the use of a full-width system of parallel key-levers moving in vertical planes, and also affords a substantial difference between the order of the types and the order of the keys. 95

A horizontal cushioned stop 82 may be provided for all the key-levers, for arresting or preventing undue springing thereof at the conclusion 100 of the down strokes.

In the diagram at Figure 6, the first eleven key-levers form a left-hand outer group, the next twenty-one key-levers form a middle group (one 110 for each of the twenty-one type-bars), and the remaining ten key-levers form a right-hand outer group. This figure differs from Figure 5, inasmuch as in Figure 5 the cross-levers 21 are connected in regular order to the left-hand and 115 right-hand groups of key-levers, while in Figure 6 the order of type-bars is different from the order of key-levers.

The first key-lever q is connected by a lever 21 to the second type-bar. The second key-lever a 120 is connected to the fourth type-bar; the third key-lever 2 is connected to the first type-bar; the fourth key-lever z is connected to the fifth type-bar; and so on, so that the order of key-levers in the left-hand and right-hand groups is 125 entirely different from the order of the types which are printed by said groups of key-levers.

Thus as seen in Figure 6 the forward types (which are in the upper rows 15 at Figure 2) are arranged in an order dissimilar to the order 130 in which the key-levers of the outside groups are arranged. Said forward types are arranged in the order 2 q 3 a s z w e x 4 d o O . 1 p ; - / ½ c and their type-bars operable by said outside levers are connected directly to the operating toggles 24, 26 to swing in a simple arc. The order of the types 33 (which are lower types at Figure 2) is c r f 5 v t g 6 b y h 7 n u j 8 m i k 9. The type-bars for these rear or lower types are connected to their operating toggles 40, 42 by 140 means of the rockable fulcrum-levers 44 and are operable by the central groups of key-levers to swing and float as described.

This disagreement with the order of the keys in the outside groups is due to the described irregular order of the connections 21, Figure 6.

It will be seen as to each type-bar, that its upper and lower types are not usually printed consecutively upon the work-sheet; as for example r and q are rarely juxtaposed, and the same is 150

true of v and s, and also of t and z, and also of b and x, and h and d, and j and l; while in many instances a numeral or punctuation-mark or fraction is put upon the same type with an alphabetical letter.

5 Variations may be resorted to within the scope of the invention, and portions of the improvements may be used without others.

Having thus described my invention, I claim:

- 10 1. A system of upstanding type-bars pivoted at their lower ends to swing rearwardly in planes converging from front to rear, and having types at their upper ends, a platen about level with the types, a key for each type-bar, a lever upon which said key is carried, a vertical link connected to each of said key-levers, cross-levers having outer and inner arms, the outer arms connected by said links to the key-levers, operating arms working in the same radial planes with their type-bars, links connecting said cross-levers to said radial operating arms, and radial links extending rearwardly from said operating arms, said type-bars having short arms extending below their fulcrum and articulated to said radial links, said operating arms pulling said radial links upwardly and forwardly and thereby swinging the type-bar to the platen.
- 20 2. A system of upstanding type-bars pivoted at their lower ends to swing rearwardly in planes converging from front to rear, and having types at their upper ends, a platen about level with the types, a key for each type-bar, a lever upon which said key is carried, a vertical link connected to each of said key-levers, cross-levers having outer and inner arms, the outer arms connected by said links to the key-levers, operating arms working in the same radial planes with their type-bars, links connecting said cross-levers to said radial operating arms, and radial links extending rearwardly from said operating arms, said type-bars having short arms extending below their fulcrums and articulated to said radial links, said operating arms pulling said radial links upwardly and forwardly and thereby swinging the type-bar to the platen, the key-levers being U-shaped, and their pivots extending in transverse lines, one line about level with the keys of the rear bank in the keyboard, and the other line about level with the keys in the front bank, the levers for the front keys being longer than the levers for the rear keys.
- 30 3. A system of upstanding type-bars pivoted at their lower ends to swing rearwardly in planes converging from front to rear, and having types at their upper ends, a platen about level with the types, a key for each type-bar, a lever upon which said key is carried, a vertical link connected to each of said key-levers, cross-levers having outer and inner arms, the outer arms connected by said links to the key-levers, operating arms working in the same radial planes with their type-bars, links connecting said cross-levers to said radial operating arms, radial links extending rearwardly from said operating arms, said type-bars having short arms extending below their fulcrums and articulated to said radial links, said operating arms pulling said radial links upwardly and forwardly and thereby swinging the type-bar to the platen, the length of the cross-lever-arms being assorted to correspond to the points to which they are connected to the key-levers, to produce uniform key depressions, hangers to which said cross-levers are pivoted, a support for said hangers, and a segment upon which the radial operating arms are pivoted and guided, said

radial operating arms overhanging the segment, and being of uniform length.

4. The combination of a platen and a system of upstanding radial two-key type-bars in front of the platen and fulcrumed at their lower ends and each carrying types at its top, said types being about level with the platen, means to enable one of the companion keys for each type-bar to swing the latter rearwardly about the fulcrum through a simple arc to the platen, to use an upper type thereon, and means to enable the other companion key to swing said type-bar about said same fulcrum and also lift said type-bar fulcrum, to bring into action a lower type thereon.

5. The combination of a platen and a system of upstanding radial two-key type-bars in front of the platen and fulcrumed at their lower ends and each carrying types at its top, said types being about level with the platen, means to enable one of the companion keys for each type-bar to swing the latter rearwardly about the fulcrum through a simple arc to the platen, to use an upper type thereon, means to enable the other companion key to swing said type-bar about 100 said same fulcrum and also lift said type-bar fulcrum, to bring into action a lower type thereon, said latter means including pivoted arms having the fulcrums for the lower ends of said type-bars, means connected to 105 the other companion key to swing the fulcrum arm to lift the type-bar fulcrum, and means co-operating with said arm for vibrating the type-bar about the fulcrum rearwardly to the platen as said fulcrum is lifted, to bring 110 into use a lower type on the type-bar; said arm and co-operating means effective to bring the lower type to exactly the same position to which the upper type was brought.

6. The combination of a platen, a system of 115 upstanding radial type-bars in front of the platen having fulcrums at their lower ends, each carrying types at its top at about the level of the platen, levers upon which said type-bars are fulcrumed, keys to swing said levers to shift the 120 type-bars radially, means acting upon the lower portions of the type-bars to restrain them while being shifted radially, so as to cause the shifting type-bars to swing rearwardly about their fulcrums to the platen, and other keys for swing- 125 ing said type-bars rearwardly while said levers are stationary.

7. In combination, a system of upstanding type-bars having types at their upper ends, an arcuate and radial system of levers whereon said 130 type-bars are fulcrumed at their lower ends, radial links articulated at their rear ends to said fulcrum-levers, each fulcrum-lever having one arm for its type-bar fulcrum and an opposite arm for its link, pivoting means for said fulcrum-levers, the latter being concentric with the arcuate array of type-bar fulcrums, means to co-operate with the fulcrum-levers to shift the type-bar fulcrums upwardly and at the same time swing said type-bars rearwardly about their fulcrums, 140 said latter means including radial operating arms to which said links are pivoted, and keys to actuate said operating arms.

8. In combination, a system of upstanding type-bars having types at their upper ends, an arcuate and radial system of levers whereon said type-bars are fulcrumed at their lower ends, radial links articulated at their rear ends to said fulcrum-levers, each fulcrum-lever having one arm for its type-bar and an opposite arm for its link, 150

5 pivoting means for said fulcrum-levers, the latter being concentric with the arcuate array of type-bar fulcrums, means to cooperate with the fulcrum-levers to shift the type-bars upwardly and swing them rearwardly, said latter means including radial operating arms to which said links are pivoted, keys to actuate said operating arms, each type-bar fulcrum being swung upwardly by its lever at the operation of its key, 10 to elevate the type-bar to bring into use a lower type thereon, and means whereby the rising type-bar is restrained at its lower end, to cause it to swing about its fulcrum when rising.

9. The combination of a system of type-bars 15 upstanding in front of the platen and having at their upper ends types about level with the platen and mounted to swing in rearwardly converging planes, a system of levers upon which the type-bars are fulcrumed at their lower ends, key-driven normally extended toggles for rocking said fulcrum-levers to shift the type-bar fulcrums upwardly, a separate system of normally extended toggles connected directly to said type-bars to restrain them while rising and thereby cause 20 the type-bars to swing rearwardly about their fulcrums, each type-bar moving rearwardly to the platen under the control of its moving fulcrum-arm and its extended stationary toggle, and keys for driving the toggles in the second set to 25 swing the type-bars rearwardly while said fulcrum-levers are held stationary by the first set of toggles; each toggle remaining stationary in extended condition while the other toggle for the same type-bar is active.

30 10. The combination of a system of type-bars upstanding in front of the platen and having at their upper ends types about level with the platen and mounted to swing in rearwardly converging planes, a system of levers upon which the type-bars are fulcrumed at their lower ends, key-driven normally extended toggles for rocking said fulcrum-levers to shift the type-bar fulcrums upwardly, a separate system of normally extended toggles connected directly to said type-bars to restrain them while rising and thereby cause the type-bars to swing rearwardly about their fulcrums, each type-bar moving rearwardly to the platen under the control of its moving fulcrum-arm and its extended stationary toggle, keys for 35 driving the toggles in the second set to swing the type-bars rearwardly while said fulcrum-levers are held stationary by the first set of toggles, each toggle remaining stationary in extended condition while the other toggle for the same type-bar is active, a returning spring for each of said toggles, and stops against which the springs normally hold the toggles in extended locking positions, whereby each toggle affords a support during the operation of the type-bar by the other toggle; each toggle operating either as a lock or as 40 an operator at each operation of the type-bar.

45 11. The combination with a platen, of a system of type-bars upstanding in front of the platen and having types at their upper ends, a radial system of levers, a segment whereon said levers are pivoted and guided, said levers having fulcrums for said type-bars, a set of operating toggles extending forwardly from said levers and including a set of links and a set of key-driven radial operating arms to which said links are pivoted, said toggles normally extended and holding said fulcrum-levers against rocking, said type-bars having short arms, and a second set of normally extended toggles including links extending forwardly from said short arms and also including a

50 set of key-driven operating arms to which such links are pivoted, said first set of toggles normally extended and holding the fulcrum-levers stationary while the type-bars are swung in simple arcs by the second set of toggles, and the second set of toggles being normally extended and guiding the short arms of the type-bars as the latter are lifted by their fulcrum-levers.

55 12. Machine constructed according to claim 11, having a returning spring for each of said operating arms; said fulcrum-levers disposed at the rear of the segment, the toggles in the first set extending over said segment, and the toggles in the second set extending under said segment.

60 13. Machine constructed according to claim 11, the toggles in one set extending crosswise of the toggles in the other set.

65 14. Machine constructed according to claim 11, having a shoulder upon each toggle for correcting the position of the companion toggle.

70 15. A system of keys, a system of two-key type-bars upstanding in front of the platen and pivoted at their lower ends to swing rearwardly against the platen, and trains connecting said keys to the type-bars and each including a lever having an arm to which the type-bar is pivoted, each train also including radial normally extended operating toggles, one of which is flexed by one key for each type-bar to rock said lever and lift the type-bar while the companion operating toggle remains in normal extended condition and takes part in swinging the type-bar about its pivot, thereby causing said type-bar to float upwardly and rearwardly as said lever is rocked, the companion key being connected to flex its operating toggle and thereby swing the type-bar in a simple arc without rocking said lever; each toggle when idle serving as a support or lock for co-operation with the active toggle.

75 16. A system of keys, a system of two-key type-bars upstanding in front of the platen and pivoted at their lower ends to swing rearwardly against the platen, and trains connecting said keys to the type-bars and each including a lever having an arm to which the type-bar is pivoted, each train also including radial normally extended operating toggles, one of which is flexed by one key for each type-bar to rock said lever and lift the type-bar while the companion operating toggle remains in normal extended condition and takes part in swinging the type-bar about its pivot and thereby causes said type-bar to float upwardly and rearwardly as said lever is rocked, the companion key being connected to flex its operating toggle and thereby swing the type-bar in a simple arc; each toggle when idle serving as a support or lock for co-operation with the active toggle, each toggle having a shoulder effective when one toggle is flexed for forcing the other toggle to extended position.

80 17. The combination of a type-bar having types fixed upon one end thereof, a lever mounted upon a fixed support, said lever being pivoted directly to the other end of said type-bar, companion keys, and means connecting said keys to said type-bar and lever and effective to swing said type-bar about said pivot when one key is operated, but effective to swing said type-bar about said pivot and also to shift the lever when the companion key is operated.

85 18. The combination of a type-bar having types fixed upon one end thereof, a lever mounted upon a fixed support, said lever being pivoted directly to the other end of said type-bar, companion keys, means connecting said keys to said type-bar and

- lever and effective to swing said type-bar about said pivot when one key is operated, but effective to swing said type-bar about said pivot and also to shift the lever when the companion key is operated, and an impression-linkage connecting said type-bar to a fixture.
19. The combination of a type-bar having types fixed upon one end thereof, a lever mounted upon a fixed support, said lever being pivoted directly to the other end of said type-bar, companion keys, means connecting said keys to said type-bar and lever and effective to swing said type-bar about said pivot when one key is operated, but effective to swing said type-bar about said pivot and also to shift the lever when the companion key is operated, and an impression-toggle pivoted at one end to the type-end of the type-bar and pivoted at the other end to a fixture.
20. The combination of a type-bar having types fixed upon one end thereof, a lever mounted upon a fixed support, said lever being pivoted directly to the other end of said type-bar, companion keys, means connecting said keys to said type-bar and lever and effective to swing said type-bar about said pivot when one key is operated, but effective to swing said type-bar about said pivot and also to shift the lever when the companion key is operated, an impression-toggle pivoted at one end to the type-end of the type-bar and pivoted at the other end to a fixture, and a flying weight to extend said toggle and effect the type-impression.
21. The combination with a type-bar, of a lever pivoted to a fixed support and having a fulcrum for said type-bar, companion keys, means connecting said keys to said type-bar and effective to swing said type-bar about said fulcrum when one key is operated, but effective to swing said type-bar about said fulcrum and also to shift the fulcrum when the companion key is operated, an impression-toggle pivoted at one end to the free end of the type-bar and pivoted at the other end to a fixture, and a second toggle pivoted at one end to the impression-toggle, and pivoted at the other end to the type-bar between its type and its fulcrum.
22. The combination of a type-bar having types fixed upon one end thereof, a lever mounted upon a fixed support, said lever being pivoted directly to the other end of said type-bar, companion keys, means connecting said keys to said type-bar and lever and effective to swing said type-bar about said pivot when one key is operated, but effective to swing said type-bar about said pivot and also to shift the lever when the companion key is operated, and an impression-linkage connecting said type-bar to a fixture, the types on said bar being equally distant from the point of pivoting of said impression-linkage to said fixture when said linkage is extended.
23. The combination with a type-bar having upper and lower types, of a lever pivoted to a fixed support and having a fulcrum for said type-bar, companion keys, means connecting said keys to said type-bar and effective to swing said type-bar about said fulcrum when one key is operated to print with the upper type, but effective to swing said type-bar about said fulcrum and also to shift the fulcrum when the companion key is operated to print with the lower type, and an impression-linkage connecting said type-bar to a fixture, the types on said bar being equally distant from the point of pivoting of said impression-linkage to said fixture when the linkage is extended, and said fulcrum-lever being co-operable with said means to float the type-bar to bring the lower type thereon accurately to printing position.
24. The combination of a platen and a system of upstanding radial two-key type-bars in front of the platen and fulcrumed at their lower ends and each carrying types at its top, said types being about level with the platen, means to enable one of the companion keys for each type-bar to swing the latter rearwardly through a simple arc to the platen, to use an upper type thereon, means to enable the other companion key to swing and also lift the type-bar, to bring into action a lower type thereon, and silent impression-devices connecting said type-bars to a fixture, and effective at all type-bar operations.
25. The combination of a platen and a system of upstanding radial two-key type-bars in front of the platen and fulcrumed at their lower ends and each carrying types at its top, said types being about level with the platen, means to enable one of the companion keys for each type-bar to swing the latter rearwardly through a simple arc to the platen, to use an upper type thereon, means to enable the other companion key to swing and also lift the type-bar to bring into action a lower type thereon, said last-mentioned means including pivoted arms having fulcrums for the lower ends of said type-bars, means connected to the other companion key to swing the fulcrum-arm to lift the type-bar, and means co-operating with said arm for vibrating the type-bar rearwardly to the platen, to bring into use a lower type on the type-bar; said arm and co-operating means effective to bring the lower type to exactly the same position to which the upper type was brought, and silent impression-devices connecting said type-bars to a fixture, and effective at all type-bar operations, and including a set of flying weights brought into motion by the type-bars and serving to impress the types upon the work-sheet.
26. The combination of a platen, a system of upstanding radial type-bars in front of the platen having fulcrums at their lower ends, each carrying types at its top at about the level of the platen, levers upon which said type-bars are fulcrumed, keys to swing said levers to shift the type-bars radially, means acting upon the lower portions of the type-bars to restrain them while being shifted radially, so as to cause the shifting type-bars to swing rearwardly about their fulcrums to the platen, and other keys for swinging said type-bars rearwardly while said levers are stationary, and silent impression-devices connecting said type-bars to a fixture, and effective at all type-bar operations, and including impression-toggles pivoted to the type-bars between the types thereon, and pivoted at their forward ends to a fixture.
27. In combination, a system of upstanding type-bars having types at their upper ends, an arcuate and radial system of levers whereon said type-bars are fulcrumed at their lower ends, radial links articulated at their rear ends to said fulcrum-levers, each fulcrum-lever having one arm for its type-bar and an opposite arm for its link, pivoting means for said fulcrum-levers, the latter being concentric with the arcuate array of type-bar fulcrums, means to co-operate with the fulcrum-levers and links to shift the type-bars upwardly and swing them rearwardly and including radial operating arms to which said links are pivoted, keys to actuate said operating arms, each type-bar fulcrum being swung upwardly by its lever at the operation of its key, to elevate the type-bar to bring into use a lower type there-

- on, and means whereby the rising type-bar is restrained at its lower end, to cause it to swing when rising, silent impression-devices connecting said type-bars to a fixture, and effective at all 5 type-bar operations, said impression-devices including normally-folded impression-toggles connecting the type-ends of the bars to a fixture, and normally folded power-transmitting toggles pivotally connecting the impression-toggles to the type-bars between the ends of the latter, and each having an impression-weight. 10
28. A narrow system of upstanding type-bars in front of a platen and pivoted at their lower ends and carrying types at their upper ends, a 15 wide system of type-bar-operating key-levers, said key-levers divided into a middle group and two flanking groups, the middle group having a lever for every type-bar, and means connecting the flanking groups of levers to the same type-bars. 20
29. A narrow system of upstanding type-bars in front of a platen and pivoted at their lower ends and carrying types at their upper ends, a wide system of type-bar-operating key-levers, 25 said key-levers divided into a middle group and two flanking groups, the middle group having a lever for every type-bar, type-bar-operating toggles, to which the key-levers in said middle group are directly connected, the width of the middle 30 group of key-levers being substantially equal to the width of the system of operating toggles, and means connecting the flanking groups of levers to the same type-bars. 35
30. A narrow system of upstanding type-bars in front of a platen and pivoted at their lower ends and carrying types at their upper ends, a wide system of type-bar-operating key-levers, 40 said key-levers divided into a middle group and two flanking groups, the middle group having a lever for every type-bar, a system of operating toggles including two rows of key-driven arms, the levers of said middle group being connected to the arms in one row, and means connecting the flanking levers to the arms in the other row. 45
31. A narrow system of upstanding type-bars in front of a platen and pivoted at their lower ends and carrying types at their upper ends, a wide system of type-bar-operating key-levers, 50 said key-levers divided into a middle group and two flanking groups, the middle group having a lever for every type-bar, a system of operating toggles including two rows of key-driven arms, the levers of said middle group being connected to the arms in one row, and means connecting 55 the flanking levers to the arms in the other row, said rows of arms being one above the other, and the key-levers in the middle group being connected to the arms in the lower row. 60
32. A narrow system of upstanding type-bars in front of a platen and pivoted at their lower ends and carrying types at their upper ends, a wide system of type-bar-operating key-levers, 65 said key-levers divided into a middle group and two flanking groups, the middle group having a lever for every type-bar, a system of operating toggles including two rows of key-driven arms, the levers of said middle group being connected to the arms in one row, and means connecting the flanking levers to the arms in the other row, 70 said rows of arms being one above the other, and the key-levers in the middle group being connected to the arms in the lower row, the levers in the flanking groups being connected to the operating arms in the upper row. 75
33. A narrow system of upstanding type-bars in front of a platen and pivoted at their lower ends and carrying types at their upper ends, a wide system of type-bar-operating key-levers, 80 said key-levers divided into a middle group and two flanking groups, the middle group having a lever for every type-bar, a system of operating toggles including two rows of key-driven arms, the levers of said middle group being connected to the arms in one row, other connections including outlying cross-levers, half of them extending from the upper arms to the left and half towards the right, and links connecting the cross-levers to the flanking groups of key-levers and to the other operating arms. 85
34. The combination of a system of parallel key-levers divided into a middle group and two flanking groups, a system of type-bars, the levers of the middle group being equal to the number of type-bars, pull-links connected to the levers in the middle group, a set of radial operating arms connected to said pull-links, supporting means for said operating arms, links extending from said operating arms, said links and arms forming extended type-bar-operating toggles working in the radial planes of the type-bars, and means connecting the flanking groups of key-levers to the type-bars. 90
35. A system of type-carriers, each having types thereon, a system of key-levers, half of said key-levers forming a middle group and being 105 connected to all of said type-carriers, a keyboard having four banks, said middle group of key-levers carrying keys in all four banks, the remaining key-levers being divided to form two flanking groups, and trains including cross-levers connecting the key-levers in the flanking groups to all the type-bars. 110
36. A system of type-carriers, each having types thereon, a system of key-levers, half of said key-levers forming a middle group and being 115 connected to all of said type-carriers, a keyboard having four banks, said middle group of key-levers carrying keys in all four banks, the remaining key-levers being divided to form two flanking groups, and trains including cross- 120 levers connecting the key-levers in the flanking groups to all the type-bars, there being twenty-one type-bars, twenty-one key-levers in the middle group, eleven key-levers in one of the flanking groups, ten key-levers in the other 125 flanking group, and twenty-one cross-levers. 130
37. A narrow system of upstanding type-bars in front of a platen and pivoted at their lower ends and carrying types at their upper ends, and two sets of operating toggles for said type-bars, 135 the toggles in one set serving as locks for co-operation with the toggles in the other set when the latter are actuated, said toggles including operating arms, one set of operating arms above the other, and the lower operating arms being directly connected to the key-levers of the middle group; the upper operating arms being cross-connected to the key-levers in one flanking group and the remainder being cross-connected to the key-levers in the other flanking group by means 140 of divergent groups of cross-levers. 145
38. A radial type-bar and operating-train system and a key-lever system which is much wider than the type-bar system and which is divided into three groups, the middle group being about the same width as the type-bar and operating-train system, and being connected directly thereto, the flanking groups extending at each side far beyond the type-bar and operating-train system and connected by right-hand and left-hand 150

groups of cross-levers to all said radial operating trains.

39. A radial type-bar and operating-train system and a key-lever system which is much wider than the type-bar system and which is divided into three groups, the middle group being about the same width as the type-bar and operating-train system, and being connected directly thereto, the flanking groups extending at each side far beyond the type-bar and operating-train system and connected by right-hand and left-hand groups of cross-levers to all said radial operating trains, each type-bar being operable by two keys, each of which is remote from the other, one key being in the middle group and the other key being in one of the flanking groups.

40. A narrow system of upstanding type-bars in front of a platen and pivoted at their lower ends and carrying types at their upper ends, a wide system of type-bar-operating key-levers, said key-levers divided into a middle group and two flanking groups, the middle group having a lever for every type-bar, a system of operating toggles including two rows of key-driven arms, the levers of said middle group being connected to the arms in one row, and means connecting the flanking levers to the arms in the other row, the lower operating arms being in proximity to the key-levers in the middle group, and below their support, and the cross-levers being above the upper set of operating arms.

41. The combination of a system of type-bars upstanding in front of the platen and having at their upper ends types about level with the platen and mounted to swing in rearwardly converging planes, a system of levers upon which the type-bars are fulcrumed at their lower ends, key-driven normally extended toggles for rocking said fulcrum-levers to shift the type-bars upwardly, a separate system of normally extended toggles connected directly to said type-bars to restrain them while rising and thereby cause the type-bars to swing rearwardly, each type-bar moving rearwardly to the platen under the control of its moving fulcrum-arm and its extended stationary toggle, keys for driving the toggles in the second set to swing the type-bars rearwardly while said fulcrum-levers are held stationary by the first set of toggles; each toggle remaining stationary in extended condition while the other toggle for the same type-bar is active, and a radially-slotted segment upon which said fulcrum-levers are mounted at the rear, the operating toggles extending forwardly, one set above said segment and the other set below said segment, the toggles in one set crossing the toggles in the other set, and including key-driven operating arms at their forward ends, said operating arms forming two sets one set above the other.

42. A system of two-key type-bars upstanding in front of a platen and pivoted at their lower ends in an arc to simply swing about the pivot toward the platen or to shift and at the same time swing about the same pivot, and said type-bars having type-heads at their upper ends, and impression-toggles connecting the type-heads to a stationary member of the machine, each type-head having four types, all of which, when the impression-toggle is extended, coincide with an arc struck from the point of the pivoting of the impression-toggle to the fixture, the toggle of each type-bar being shiftable with the type-bar but having substantially the same extension and therefore substantially the same printing effect

when the type-bar is operated by either of its keys.

43. The combination of a system of upstanding key-controlled fulcrumed type-bars pivoted at their lower ends and carrying types at their upper ends, a platen about level with the upper ends of the type-bars, the latter working in planes which converge rearwardly, and impression-devices for said type-bars, said impression-devices each including a normally folded impression-toggle pivoted at its rear end to the top portion of its type-bar, and pivoted at its forward end to a fixed support in the machine, said impression-toggle being extended when the type is in printing position, and each impression-device also including a transmission-toggle which is pivoted at one end to said impression-toggle and at the other end to the type-bar between the type and fulcrum of the latter, said impression-toggle having a weight, and transmitting the momentum of the weight to the impression-toggle, to impress the type silently against the platen.

44. Machine constructed according to claim 43, in which the compound toggle is arranged in respect to the type-bar so that it is extended by force derived from the type-bar.

45. Machine constructed according to claim 43, in which said weight is fixed upon an arm which is pivoted to the type-bar; said arm projecting forwardly from the type-bar between its ends and above the segment to which the type-bars are connected at their lower ends, all four members of each compound toggle operating in the same radial plane with its type-bar, and a spring-finger upon the type-bar which is flexed by the compound toggle and acts upon the same to start the re-folding operation, and a returning spring from the type-bar.

46. Machine constructed according to claim 43, in which each of said type-bars has four types thereon, each impression-toggle being pivoted to its type-bar at a point about midway of the four types, said types coinciding with an arc struck from the fixed pivot of the extended impression-toggle, key-operated levers upon which said type-bars are fulcrumed at their lower ends, and means co-operating with said fulcrum-levers to float the type-bars upwardly.

47. A system of two-key type-bars upstanding in front of a platen and pivoted at their lower ends in an arc and having type-heads at their upper ends, impression-toggles connecting the type-heads to a stationary member of the machine, transmission toggles connecting the impression-toggles to the type-bars, each type-head having four types, all of which, when the compound toggle formed by the transmission toggle and impression-toggle is extended, coincide with an arc struck from the point of the pivoting of the impression-toggle to the fixture, and means for calling the compound toggle into effective action for either a swinging motion of the type-bar through a simple arc or a bodily rising and swinging motion of the type-bar, the compound toggle having only one point of connection with the fixed frame of the machine, and two points of connection with the type-bar.

48. A system of two-key type-bars upstanding in front of a platen and pivoted at their lower ends in an arc and having type-heads at their upper ends, and impression-toggles connecting the type-heads to a stationary member of the machine, each type-head having four types, all of which, when the impression-toggle is extended, coincides with an arc struck from the point of the pivoting of the impression-toggle to the fix-

ture, the toggle of each type-bar having substantially the same printing effect when the type-bar is operated by either of its keys, each type-bar being provided with lower case letters or characters which are not usually operated in immediate succession, so that no type-bar will usually be called into operation to make an uninterrupted succession of type-impressions on the work-sheet.

49. A narrow system of upstanding type-bars in front of a platen and pivoted at their lower ends and carrying types at their upper ends, a wide system of type-bar-operating key-levers, said key-levers divided into a middle group and two flanking groups, the middle group having a lever for every type-bar, a system of operating toggles including two rows of key-driven arms, the levers of said middle group being connected to the arms in one row, other connections including outlying cross-levers, half of them extending from the upper arms to the left and half towards the right, and links connecting the cross-levers to the flanking groups of key-levers and to the upper operating arms, the outlying cross-levers being arranged out of alphabetical order with respect to their key-levers.

50. A radial type-bar operating-train system and a key-lever system which is much wider than the type-bar system and which is divided into three groups, the middle group being about the same width as the type-bar and operating-train system, and being connected directly thereto, the

flanking groups extending at each side far beyond the type-bar and operating-train system and connected by right-hand and left-hand groups of cross-levers to all said radial operating trains, the alphabetical order of the types which are operated by key-levers in the middle group agreeing with the keys in that group, but the order of the cross-levers being out of alphabetical correspondence with the order of their key-levers.

51. A radial type-bar operating-train system and a key-lever system which is much wider than the type-bar system and which is divided into three groups, the middle group being about the same width as the type-bar and operating-train system, and being connected directly thereto, the flanking groups extending at each side far beyond the type-bar and operating-train system and connected by right-hand and left-hand groups of cross-levers to all said radial operating trains, each type-bar being operable by two keys, each of which is remote from the other, one key being in the middle group and the other key being in one of the flanking groups, the type-bars having upper and lower rows of types, the order of types in the upper row upon the type-bars being c r f 5 100 v t g 6 b y h 7 n u j 8 m i k 9 , and the order of the lower types upon the type-bars, which are connected to the cross-levers, being 2 q 3 a s z w e x 4 d o 0 . 1 p ; - / 1/2 ¢.
